UNITED STATES PATENT OFFICE

2,005,330

ELECTRON EMISSION DEVICE

Thomas W. Sukumlyn, Los Angeles, Calif.

Application August 19, 1930, Serial No. 476,323

11 Claims. (Cl. 250—27.5)

This invention relates to a device utilizing electron emission, and especially one that can be used as a cathode ray tube, or as an amplifier of electrical impulses.

5 This application is a continuation in part of my prior application, Serial No. 444,427, filed April 15, 1930, and entitled: "Vacuum tube device."

In that application I describe several forms 10 of electron emission devices in which a directing anode is utilized to confine the electron or ion stream, and especially by the aid of converging passages that overcome the effect of any tendency of the electron stream to spread.

15 It is one of the objects of my present invention to make it possible to adjust the degree of convergence of the beam, and especially by adjusting the potential of the directing anode, or of each wall thereof.

20 It is still another object of my invention to provide a directing anode, which is formed of two or more converging axially displaced members, whereby a more accurate control of the stream from the cathode is possible.

25 The stream of electrons emanating from the cathode and ions coexisting with the electrons, are spread out over an area corresponding to the surface of the cathode, thus forming a wide base, narrowing as controlled by the directing anode in a manner hereinbefore specified. By using a control electrode or grid near the wide base, and conforming to the cathode, beneficial effects are secured. The control electrode or grid, being arranged close to the base 30 of the stream, has a relatively large active area, whereby a more accurate and wider control is possible. Furthermore, no material concentration of any ionization on the grid is likely; and accordingly it is another object of my invention 35 to provide an effective relative arrangement between the cathode and the grid.

40 It is still another object of my invention to provide an element in the tube that serves to remove any collection of positive ions near the control electrode or filament, and thus to prevent any undesired effects. This element is especially useful in gas-filled tubes, such as may be common for Braun tubes.

45 My invention possesses many other advantages, and has other objects which may be made more easily apparent from a consideration of several embodiments of my invention. For this purpose I have shown a few forms in the drawings accompanying and forming part of the 50 present specification. I shall now proceed to de-

scribe these forms in detail, which illustrate the general principles of my invention; but it is to be understood that this detailed description is not to be taken in a limiting sense, since the scope of my invention is best defined by the appended claims.

5 Referring to the drawings:

Figure 1 is a diagrammatic representation of one form of electron emission device which embodies my invention, the connections to the external circuits being indicated;

Fig. 2 is a view, taken along plane 2—2 of Fig. 1; and

Fig. 3 to 6 inclusive are similar diagrammatic sectional views of modified forms of the tube.

15 This filament 18 is shown as heated by the passage of an electric current through it, and supplied from a source 19. The anode 14 is connected to the cathode 18 as by a conductor 20. A source of plate potential 21 is included in this 20 connection. A translating device 22 also can be interposed in this external circuit. This translating device represents a general class of devices, which can utilize or transmit the space 25 current variations; for example a transformer or the like.

25 Interposed in the space between the electrodes 14 and 18 there is a directing anode structure 23. This structure is such that it converges the stream of electrons from the cathode 18 toward 30 the center of the plate or anode 14. To facilitate this effect, the cathode 18 is shown as annular in form. The plane of the cathode is substantially perpendicular to the axis of the electron stream. In the present instance the cathode is 35 shown as a ribbon with its edge disposed toward the anode 14. Close to and conforming with this edge, an annular space 24 is formed between the two truncated hollow cones 25 and 26 which comprise the directing anode structure 23. It 40 is also desirable to include a shield 27 between members 18 and 23, and which could be used as a controlling grid. It can be either negative or positive with respect to the cathode 18. In this 45 instance, I show it used with a negative bias, as by being joined to the negative terminal of the heating battery 19, and the connection including an input coil or transformer 38.

50 The truncated cones 25 and 26, being arranged to converge toward the anode 14, provide a continuous annular space through which the electrons travel toward plate 14. I have indicated by the dotted lines 28 the path of these electrons under ideal conditions. In practice, however, there is still some divergence from the true 55

conical form, due to the mutual repulsion effect between the electrons. However, the converging path 24 materially restricts the electrons against spreading out, and the result is that an electron stream of comparatively large concentration is obtained.

In order to adjust the degree of concentration of the stream 28, I provide electrical means for setting the relative potentials of the members 10 25, 26, and cathode 18. The potentials of either or both members 25, 26 can be adjusted, as by the aid of a tap 44 on a battery 39, located in a circuit 40 between the cathode 18 and the member 25. Similarly, the potential of member 26 15 can be set by proper choice of potential for battery 41 located in this circuit 40, and to the positive side of which the member 26 connects, as by a lead-in rod 42. A similar lead-in 43 is shown for member 26.

20 By this means, any degree of convergence (within limits) of stream 28 can be obtained.

In order to obtain a greater control of the stream 28, any desired series of coaxial directing anode members can be used, any or all of 25 which has an adjustable potential. Thus in Fig. 3, there are shown substantially the same type of tube as in Fig. 1, except for the matters now to be detailed.

The directing anode structure in this form 30 includes two pairs of axially spaced truncated cones. One set, 29 and 30, nearest the grid 27 is electrically joined to the lead-in rod 31. The other set, 32 and 33 define a slightly wider annular space for stream 28 and forms a virtual 35 extension of the truncated cone structure formed by members 29, 30. The degree of convergence of members 32, 33 can be different from that of members 29, 30. The inner member 33 can be joined electrically to members 29, 30, as by connection 34 so that all three of these members are at the same positive potential of battery 41. The outer member 32 can be joined to a lead-in rod 35 connected to a top 36 on battery 39.

The cathode or filament 37 is shown in this 45 instance as formed of two turns. In order to lead off any undesired positive ions (in case a gas filled tube is used) from the neighborhood of cathode 37 and grid 27, an electrode 44 of plate form can be disposed below the cathode 50 and kept at a proper potential as by a battery 45.

It is to be noted that in both forms of Figs. 1 and 3, the grid electrode 27 and cathode 18 or 37 have an effective length conforming with the annular base of the stream 28. In this 55 way, no serious concentration of ions can be secured on any spot on these electrodes, thus permitting the grid to perform its function accurately.

Instead of having axially displaced directing 60 anode pairs, they can be concentric, as shown for example in Fig. 4. In this case the stream 28 is directed through a plurality of concentric converging annular spaces, defined respectively by the sets of members 46, 47, and 48, 49. The 65 potentials of the outer members 46, 48 can be the same as by being joined to a common lead-in 50; and that of the inner members 47, 49 can also be the same, as by being joined to a common lead-in 51. It is of course understood 70 that both these potentials can be adjusted to secure the desired degree of convergence.

Grid 52 of course has a plurality of spaces 75 53, 54 conforming with the plurality of concentric annular spaces of the directing anode,

as well as with the configuration of cathode 55.

Fig. 5 shows a form of the device which is a combination of Figs. 3 and 4. Thus there are four sets of concentric members forming the directing anode structure. Two of these sets such as 56, 57, and 58, 59 are concentric; while the other two sets 60, 61 and 62, 63 form respectively axial extensions of the sets 56, 57 and 58, 59. In this form, the inner members 59, 63, 51, 61, are joined electrically together 10 and to the outer members 56, 58. A common lead-in 64 is provided for these six members. The outer members 60 and 62 of the superimposed extension are also joined together and to a common lead-in 69. By proper adjustment of the relative potentials of these two members 60, 62 and of the others forming the directing anode structure, the desired adjustment of the degree of convergence of beam 28 can be obtained. 20

In both forms of Figs. 3 and 5, the axially spaced sets define annular spaces that are wider as the convergence proceeds. This is useful to ensure that any widened stream at the discharge end of the bottom set of members will 25 be accommodated.

It is of course possible to use the device in gas-filled tubes for effecting a fluorescent coating on the end of the tube. Such a structure is shown diagrammatically in Fig. 6, in which 30 the tube 65 has an enlarged end 66 coated with a layer 67 of fluorescent material, such as calcium tungstate. An electromagnetic or electrostatic control can be provided for the converged stream 28; in this instance an electromagnetic 35 control is indicated by the aid of coils 68. I claim:

1. An electron emission device, comprising a cathode, a directing anode providing a converging path for the electron stream from the cathode, said directing anode being formed of a plurality of converging nested members, an envelope for the electrodes, and at least one of said members and said cathode being adapted to have the relative potential therebetween adjusted. 45

2. An electron emission device, comprising a cathode, a directing anode, said anode being formed of a plurality of axially displaced members forming a converging path for the stream 50 of electrons, said converging paths being defined by nested members, an envelope for the cathode and the anode, said means having a converging electron path, and at least one of 55 said members and said cathode being adapted to have the relative potential therebetween adjusted.

3. An electron emission device, comprising a cathode having an extended area, means for 60 converging the stream of electrons as they progress from the cathode, and a control electrode arranged with its active length conforming to the base of the means forming the path for the converging stream, and an envelope for the 65 cathode the converging means and the control electrode.

4. An electron emission device, comprising a cathode for emitting electrons from a wide base, means for converging the stream of electrons 70 as they progress from the cathode, said means having a converging electron path, a control electrode arranged with its active length conforming to the base of the means having the path for the converging stream, and an envelope 75

for the cathode the converging means and the control electrode.

5. An electron emission device, comprising a cathode having an active length from which a stream of electrons is emitted, the stream being directed toward one end of the tube, the base of the stream conforming to the active length of the cathode, a control electrode adjacent the cathode and having a form conforming therewith, a member upon which the electrons are received another electrode back of the cathode for receiving ions proceeding in a direction opposite the desired stream of electrons and an envelope for the electrodes.

10 15 6. The combination as set forth in claim 5, in which means are included for converging the stream of electrons.

7. The combination as set forth in claim 5, in which the control electrode defines an opening which is disposed opposite the convolutions of the cathode, said convolutions being disposed to define a passageway opposite the opening.

20 25 8. An electrode structure for directing electrons in an electron emission device, comprising a plurality of sets of converging nested members, each set having at least two such members, said members forming between them a converging

space, and the sets being axially spaced with respect to each other.

9. An electrode structure for directing electrons in an electron emission device, comprising a plurality of sets of converging nested members, each set having at least two such members, and the sets being axially spaced with respect to each other, the nested members forming annular passageways, the width of the passageways of a succeeding set being greater than that of the preceding set.

10 15 10. An electrode structure for directing electrons in an electron emission device, comprising a plurality of sets of converging nested members, each set having at least two such members, and the sets being axially spaced with respect to each other, and means for electrically connecting the inner of the members together.

20 25 11. An electron emission device, comprising a cathode, and a directing anode, said anode being formed of a pair of annular metallic members defining an annular converging path between them for the electrons emitted from the cathode, each of said members being adapted to be maintained at a different potential value with respect to said cathode.

THOMAS W. SUKUMLYN.
